UNITED STATES PATENT OFFICE.

JACOB M. MARCH, OF WASHINGTON, DISTRICT OF COLUMBIA.

INSIDE TRUNK-BRACE.

SPECIFICATION forming part of Letters Patent No. 315,046, dated April 7, 1885.

Application filed January 16, 1885. (No model.)

To all whom it may concern:

Be it known that I, JACOB M. MARCH, of Pennsylvania, residing at No. 1522 16th street, northwest, Washington, District of Columbia, have invented a new and original Improvement in Combined Inside Trunk-Braces, of which the following is a specification, reference being had to the accompanying drawings, forming a part thereof.

- 10 The general object of this invention is to securely protect trunks, packing-boxes, or other similar structures from being crushed in by rough handling or by any undue pressure upon the outer surfaces, and to cause the articles placed therein, no matter how many or how few there may be, to be at all times and under all circumstances kept intact by the combined brace being adjusted vertically at any given or desired intervals, as occasion 15 may require, and to prevent the trunk or other similar structure from yielding at the corners.
- 20
- 25

Figure 1 represents the trunk with brace. Fig. 2 represents the brace. Fig. 3 represents the corner-socket in trunk. Fig. 4 represents the socket attached to wall of trunk, A A' and B B' being different views of Figs. 3 and 4.

In the brace, Fig. 2, *e e* represent the hinges, by means of which the brace is opened or closed at will, *f* being a bar or keeper, which turns upon a central pivot, *d*, and, passing over the spring *C*, located on the hinged brace on opposite sides of the keeper, enters the socket or clasp *b* on side wall of trunk, and 35 holds in place the combined brace, as shown in Fig. 1.

The socket shown in Fig. 3, and at *a a'*, is the metallic clasp or support to be adjusted in the corners of the trunk, and which receives the corners or ends of the combined brace, the lower shelf of which shall be made somewhat more projecting than its upper shelf, in order to receive the corners of the brace, Fig. 2, and conduct it to its proper position.

45 The clasp or socket shown in Fig. 4, and at B B', is intended to be affixed to the side walls of the trunk in such manner as to receive the edge of the brace, Fig. 2, and the ends of the keeper *f* after it shall have been moved past the spring *c*. The metallic corners and side

5 sockets or clasps are to be screwed or riveted and clinched on the outer surface of the trunk. The several parts of the foregoing hinged brace, corner-braces, side clasps, and each and every part thereof may be made of wood, wire, cast-iron, brass, or of any material suitable for the purpose.

In the use of the combined brace no trunk need be deprived of its top tray as now used, the corner-sockets hereinbefore described furnishing the necessary support therefor.

What I claim is—

1. In a trunk, a brace composed of two sections hinged together, in combination with the keeper pivoted thereto, substantially as described.
2. In a trunk, a brace composed of two longitudinal sections hinged together, substantially as described, in combination with a keeper pivoted thereto, substantially as described, and for the purposes set forth.
3. The combination of a trunk-brace composed of two sections hinged together, substantially as described, with a keeper pivoted thereto, and a socket attached to the walls of the trunk to receive the ends of the keeper, all substantially as described, and for the purposes set forth.
4. In a trunk, a combined corner-brace and socket having top and bottom shelves or supports, the former being made smaller to allow of a more ready admission of the brace, substantially as set forth, and for the purposes herein described.
5. The combination of a trunk provided with corner-braces and keeper-sockets with the hinged brace provided with the pivoted keeper, substantially as described, and for the purpose set forth.
6. In a trunk, the longitudinally-hinged brace provided with the pivoted keeper *f* and the retaining-springs *c c*, located so as to engage opposite sides of said keeper, all substantially as described, and for the purpose set forth.

J. M. MARCH.
